UNITED STATES PATENT OFFICE

WILLIAM S. PIPER, OF LIBERTY, MISSOURI

AUTOMATIC FIRE-ALARM SYSTEM

Application filed April 29, 1926. Serial No. 105,476.

- This invention relates to improvements in automatic fire alarm systems, and refers more particularly to an automatic fire alarm device which may be located at any desired point in a structure or building,—including dwellings, industrial structures, manufacturing buildings or storage warehouses, and may be used in apartment buildings when attached to electric annunciators.
- 10 The novelty in the invention lies primarily in the utilizing of a fusible link in connection with a gravity switch which, when closed, completes an electric circuit and rings an automatic alarm.
- 15 Fig. 1 is a view of a small dwelling or gambrel roof with the device in place.
- Fig. 2 is a plan view of the construction shown in Fig. 1 with part of the roof broken away to show the positioning of the device.
- 20 Fig. 3 shows an electric circuit and the fire alarm bell.
- Fig. 4 is an enlarged detail of the device as installed.
- Fig. 5 is a view taken along the line 5—5 in 25 Fig. 4, looking in the direction of the arrows.
- Fig. 6 is an edge view of the device shown in Fig. 4.
- Fig. 7 is a modified type of construction in which the fusible link is mounted upon the 30 exterior of the box containing the switch,—that is, the box is placed inside of a wall and only the link being outside of the box.
- Fig. 8 is a view showing the construction of Fig. 7 and taken from the opposite side of 35 the switch box.
- Fig. 9 is a view taken along the line 9—9 in Fig. 7.
- Referring to the drawings, at 1 in Fig. 1 are shown rafters supported by perpendicular lateral joists 2 and a ridge pole 3. The 40 simplest type of building construction is shown, as the building in which the device is used forms no part of the present invention. In Fig. 1 the circuit closers are positioned at any predetermined point such as at 4 along the rafters and also at 4 on the perpendicular joists. The circuit closer is shown in detail 45 in Fig. 4 and consists of a switch box 5 in which is mounted a gravity switch 6 having a support member 7 to which is pivoted at 8 a bell crank 9 at the outer extremity of which is mounted a weight 10. At the opposite extremity of the bell crank designated as 9^a is attached a secondary connection 11 which, in turn, is connected to a fusible link 12. This latter link 12 consists of two pieces of metal soldered together by means of a metallic soldering material of a predetermined melting point. This solder is adapted to melt at a temperature which is recognized as a proper 55 temperature by the Fire Underwriters Laboratories. This link has eyes at both ends, designated as 12^a and 12^b, one eye member attached to a stationary hook member 13 and the opposite eye designated as 12^a attached to the secondary connection 11. The stem 9 of the bell crank has the form of a knife-edge switch which is adapted to fall between the bifurcated portions of the contacting members of the switch 6 designated as 13 in the drawings. The switch has electric connection 14 and 15 with the circuit wires 16 and 17, respectively, in which circuit are interposed the alarm bell 18 and the battery 19. The principle of the device, which is very 60 simple in operation relying wholly upon gravitational forces, consists of the closing of the circuit due to the falling of the weight 10 with the fusing of the link 12.
- The modified form of construction is shown 65 in Figs. 7 and 8 and 9 and differs in this construction relative the one described consisting in mounting the link 12 upon the switch box instead of arranging it as shown in Fig. 4. The modified type of switch would be more 70 adaptable to a location where the room for the device was limited.
- In the drawings the device is shown mounted within a switch box. It is understood that 75 while this construction would probably be less affected by deteriorating forces such as dampness and the collection of dust and dirt, the invention is not restricted to the use of a device which is wholly enclosed or partially so. Furthermore, in place of having a special alarm circuit with a battery such as that shown in Fig. 3, the device may as well be connected in the light circuit by the 80 use of a transformer and the alarm bell func- 85

tioned from power supplied from the lighting circuit.

It will be noted, also, that there has been eliminated from the device any considerable length of wires or connections, and in addition, any mechanism which might produce faulty functioning of the device with the melting and separating of the fusible links. The device is positive in operation, relying wholly upon the forces of gravity acting upon the weight to close the switch when the fusible link is parted due to excessive heat.

The positioning of the device in a building or structure is dependent more or less upon the likelihood of fire in a particular part of the building. It has been found that fires usually occur in the roof or in the basement of a structure, so consequently, in the drawings, we have shown the device attached to the rafters of a dwelling house in order merely to disclose a characteristic positioning of the device. While only two types of the device are shown, it is understood that the idea broadly covered is a simple gravity switch mechanism directly connected to a fusible link member which is connected into an electric circuit to function an alarm bell with the fusing or melting of the link.

A decidedly advantageous feature in connection with this system of fire alarm would be to have the wires of the electric circuit carried in insulated conduits. Enclosing the wires in conduits would increase materially the efficiency of the system, as it would prevent the burning off of insulation and failure of the system. Where the system depended upon uncovered but insulated wires, the heat, if in close vicinity to the wires, might burn off the insulation and melt the wires before melting the fuse. Insulated conduits would obviate this.

I claim as my invention:

1. In a gravity circuit closer for an automatic fire alarm system, a casing, a pivoted bell-crank in the casing having a knife edge on one arm, bifurcated members adapted to receive and coact with the knife edge, a weight on the knife edge arm, a link connected to the other arm of the bell-crank lever, and a fusible element arranged exteriorly of the casing and above the bottom of the latter, and comprising two metallic members joined by a film of solder associated with the link, whereby to retain the knife edge out of operative contact with the bifurcated members.

2. In a gravity circuit closer for an automatic fire alarm system, a closed casing, a rock shaft extending through one of the walls of the casing, a weighted arm fixed to the rock shaft and located within the casing, said arm having a knife edge, another arm fixed to the external portion of said rock shaft, the arms and rock shaft forming a bell crank, a bifurcated member adapted to receive and cooperate with the knife edge, a fixed sup-

port on the exterior of the casing, and a fusible element connecting said support to the external arms, said fusible element comprising two metallic elements joined by a film of solder whereby to retain the knife edge out of operative contact with the bifurcated members.
